UNITED STATES PATENT OFFICE.

ERNST PETERSON, OF ROCKFORD, ILLINOIS.

CIGARETTE AND MATCH DISPENSER.

Application filed July 22, 1926. Serial No. 134,114.

This invention relates to improvements in cigarette and match dispensers, and has for one of its principal objects the provision of means for readily and efficiently dispensing 5 matches, cigarettes and the like, to a user or customer, and has for one of its particular objects means for simultaneously presenting both a match and a cigarette for use.

One of the important objects of this invention is to provide a combination match and cigarette dispenser which can be conveniently applied to an automobile, particularly the dash-board or similar portion thereof, and which dispenser can be operated 10 by one hand, thereby making the same convenient to the driver of the automobile or other vehicle without necessitating stoppage of the car for said purpose.

Other and further important objects of the invention will be apparent from the disclosures in the accompanying drawings and following specification.

The invention, in a preferred form, is illustrated in the drawings and hereinafter 25 more fully described.

In the drawings:

Figure 1 is a perspective view of the improved combination match and cigarette dispenser of this invention.

Figure 2 is a sectional view, taken approximately on the line 2—2 of Figure 1.

Figure 3 is a detail sectional view, taken on the line 3—3 of Figure 2, parts being omitted.

Figure 4 is a perspective view of the lower portion of the operating handle of the device, and

Figure 5 is a detail view illustrating a slight modification.

As shown in the drawings:

The reference numeral 10 indicates generally a case for the improved combination cigarette and match dispenser of this invention, which case may be of any desired or 45 convenient shape and provided with supporting brackets or the like 12 whereby the same can be readily and conveniently attached to a wall, the dashboard of an automobile, or a similar object.

A slot 14 is provided in the top of the case adapted for the passage of a cigarette therethrough, and a corresponding similar though smaller slot 16 is also provided in the top of the case adapted for the passage there- 55 through of a match.

As best shown in Figure 2, a V-shaped

space for the reception of cigarettes 18 or the like is provided in the receptacle, and at the lower apex of this V-shaped space is positioned the upper end of an ejecting member 20 which slides in a suitable slide or runway 21 formed in the ends of the case 10.

The upper end of the ejector 20 is also V-shaped or grooved as shown at 23 so as to receive but a single cigarette or match, and to maintain the same in position during the upward movement of the ejector regardless of the number of remaining similar articles in the space.

This ejecting member 20 is operated by means of a handle 22, the outer end of which projects to the outside of the casing, and which is pivoted on suitable bearings 24 mounted in the wall of the casing and which 75 has projecting fingers 26 or the like, best shown in Figure 4, which operate the match and cigarette dispensing members in an obvious manner.

Helical springs 30 are provided attached 80 to the bottom of the ejecting member 20 and to the bottom of the case 10 so as to assist gravity in bringing the ejecting member to its lowermost position after a cigarette and match have been ejected.

As shown in Figure 5, the handle 22 may be provided with a projection 32, part of which comprises a leaf spring 34 having a ledge or the like 36 attached to the under face thereof, which contacts with a suitable 85 locking pin 38 mounted on the casing whereby the handle can be retained in its lowermost position in order to afford the operator an opportunity to remove the match and cigarette. A stop 39 is provided as shown in Figure 2, whereby the lowermost position of the handle is positively fixed, so that the ejector 20 will not project beyond the top of the casing 10.

It will be obvious that herein is provided 100 a ready, suitable, and economical and convenient means for dispensing both matches and cigarettes at the same time, or any other similar or desired objects. Further, the device can be operated entirely with one 105 hand, thereby making it particularly convenient for automobile drivers or the like. Again, the device is ornamental and can be made in various shapes and sizes, as desired or convenient.

I am aware that many changes may be made and numerous details of construction

varied throughout a wide range without departing from the principles of this invention, and I therefore do not purpose limiting the patent granted hereon otherwise than as 5 necessitated by the prior art.

I claim as my invention:

In a combined cigarette and match dispenser, a receptacle for the objects to be dispensed, a pair of ejector plates passing 10 upwardly through said receptacle to dispense two objects at one ejecting movement, and a forked handle for moving both of said eject-

ing means, said handle being pivoted on the interior wall of the casing and having its manually operated end positioned alongside 15 the outer wall of the casing, together with springs for returning the ejector members to original position after an ejecting movement, and latch means for locking the handle in object ejecting position against the tension of said spring.

In testimony whereof I affix my signature.

ERNST PETERSON.
